(57) **CLAIM**

The ornamental design for a medical elongate advancer as shown and described.

DESCRIPTION

FIG. 1 is a front, left perspective view of a medical elongate advancer;

FIG. 2 is a rear, left perspective view thereof;

FIG. 3 is a left elevational view thereof;

FIG. 4 is a right elevational view thereof;

FIG. 5 is a front elevational view of the medical elongate advancer, shown enlarged for clarity of disclosure;

FIG. 6 is a rear elevational view thereof, shown enlarged for clarity of disclosure;

FIG. 7 is a top plan view of the medical elongate advancer shown at a typical scale; and,

FIG. 8 is a bottom plan view thereof.

In the drawings, the equal-length broken lines on the surface of the medical elongate advancer depict portions of the article that form no part of the claimed design. The equal-length broken lines showing an elongate member depicts environmental structure and forms no part of the claimed design. All broken lines form no part of the claimed design.

1 Claim, 8 Drawing Sheets
